CLAIM

The ornamental design for a front fork for a bicycle, as shown and described.

DESCRIPTION

FIG. 1 is a perspective view of a front fork for a bicycle showing our new design;

FIG. 2 is a front elevation view thereof;

FIG. 3 is a rear elevation view thereof;

FIG. 4 is a right side elevation view thereof;

FIG. 5 is a top plan view thereof; and,

FIG. 6 is a bottom plan view thereof.

The left side view of the fork is a mirror image of the right side elevation view shown.

FIG. I

FIG.2
